COMBINATION MAILBOX AND PARCEL POST CARRIER

Nick C. Helten, Calio, N. Dak.

Application June 29, 1937, Serial No. 151,001

3 Claims. (Cl. 232—39)

The invention relates to a combination mailbox and parcel post carrier and more especially to a rural mail receiving and delivery apparatus.

The primary object of the invention is the provision of a device of this character, wherein the mailbox is separate and independent from the parcel post carrier, the latter being adapted for tilting movement and on the tilting thereof automatically opens for the introduction of parcel post matter therein while the mailbox proper is supported for sliding and swinging movements and is adapted for rural service in the reception and delivery of mail matter, being novel in its make-up.

Another object of the invention is the provision of a device of this character, wherein the same is supported by a stand and will receive and deliver mail matter both letters, parcel post packages or the like, being weatherproof and on the opening of the door of the mailbox the mail matter within the same can be readily picked up and also a mail deliveryman or carrier is enabled to place mail matter within the box more conveniently in that the box under its movable mounting can be pulled close to the deliverer of the mail matter when within a vehicle thus avoiding the necessity of leaving the vehicle for the picking up or delivery of mail matter.

A further object of the invention is the provision of a device of this character, wherein the construction thereof in its entirety is novel and enables the quick handling of mail and parcel post matter either in the receiving thereof or the delivery of the same.

A still further object of the invention is the provision of a device of this character, which is comparatively simple in construction, thoroughly reliable and efficient in operation, convenient for the handling of mail matter and parcel post matter in rural districts, strong, durable, and comparatively inexpensive to manufacture and install.

With these and other objects in view, the invention consists in the features of construction, combination and arrangement of parts as will be hereinafter more fully described, illustrated in the accompanying drawings, which disclose the preferred embodiment of the invention and pointed out in the claims hereunto appended.

In the accompanying drawings:

Figure 1 is an end elevation of the device partly in section constructed in accordance with the invention.

Figure 2 is a rear elevation thereof partly in section.

Figure 3 is a sectional view taken on the line 3—3 of Figure 2 looking in the direction of the arrows and showing by full lines the normal upright position of the parcel post receiver and by dotted lines the tilted open position thereof.

Figure 4 is a fragmentary sectional view taken on the line 4—4 of Figure 2 looking in the direction of the arrows.

Figure 5 is a fragmentary sectional view taken on the line 5—5 of Figure 2 looking in the direction of the arrows.

Figure 6 is a top plan view of the mailbox and parcel post carrier in normal position.

Figure 7 is a view similar to Figure 6 showing the parcel post receiver in an open position with the mailbox released therefrom.

Similar reference characters indicate corresponding parts throughout the several views in the drawings.

Referring to the drawings in detail, the device comprises a stand A involving vertically disposed or perpendicular uprights or end posts 10 and a lower connecting bar 11 joined with the uprights or posts by the unions 12 while at the upper ends of these uprights or posts are fittings 13 and 14, respectively, for an upper rocking bar or tube 15. Located between the bars 11 and 15 and also the uprights or posts 10 connected therewith is a parcel post receiver in the form of a trough-like body 16 and to its rear wall is connected by hinges 17 a vertically swinging cover or top 18. The bar 15 is susceptible of rocking movement and has fixed therein depending arms 19, these being pivoted at 20 exteriorly to opposite ends of the cover or top 18 so that on the swinging of the body 16 from an upright or perpendicular position to a forwardly tilted position the cover or top 18 will be automatically opened giving access to the interior of the body for the placing of parcel post packages or the like therein or their removal therefrom. The body 16 has fixed thereto bearings 21, these rotatably fitting the bar 11 to allow for tilting movement of the body 16, the bar 11 being the axis about which the body 16 swings. When the body 16 is returned to normal upright or perpendicular position, the cover or top 18 automatically closes thereon.

One of the uprights or posts 10 has a rotatable upper section 22 carrying an outwardly directed horizontally disposed forked bracket 23 which is made secure to said section 22 and swings in a horizontal plane laterally to one side of the stand A to be at right angles forwardly with respect to the latter or beyond one end of said stand and substantially parallel therewith. This bracket

supports a bed 24 provided longitudinally thereof with spaced parallel tracks 25 fitted with runners 26 at the bottom of a mailbox proper 27 and in this manner the latter is slidably fitted 5 upon the bed 24 so that it can be extended or re-treated at the option of the user thereof.

The box 27 at its open front is provided with a vertically swinging door 28 hinged at 29 and exteriorly thereof is a hand grip 30 convenient for 10 the opening and closing of said door 28.

On the body 16 constituting the parcel post receiver at the end thereof next to the box 27 is arranged a latching trigger 42 which is pivoted at 43 and is operable by a hand grip 44, the trigger 42 being designed to latch the body 16 in an upright or perpendicular position by engaging a lug 45 on and rising from a swinging arm 46 fixed to the turning section 22. This arm 46 carries a pivoted latching pawl or dog 47 engaged 20 with a keeper extension 48 fixed to the upright or post 18 immediately below the turning section 22 and the path of movement of the arm 46. This pawl or dog 47 when engaging the keeper extension 48 latches the bracket 23 in a forwardly extended position at right angles to the stand A so that the mailbox 27 will be at right angles to the receiver body 16 and forwardly of the stand A carrying the latter. When the pawl or dog 47 is released from the keeper extension 48, 30 the bracket 23 can be swung horizontally in a lateral direction away from the receiver body 16. On the bracket 23 close to the door end of the box 27 is a cranked control lever 49 which through linkage 50 connected with the pawl or dog 47 will operate the latter to release the same from the keeper extension 48. This lever has associated with it a spring 51 which is for the purpose of having the dog or pawl 47 automatically latch with the keeper extension 48 when 35 the bracket 23 is swung to a position forwardly of the stand A and at right angles thereto and thus secure the arm 46 in a position to have the latching trigger 42 engage with the lug 45 on this arm and thus fasten or hold the parcel post receiver body 16 in an upright or normal perpendicular position in the stand A. The latching trigger 42 is releasable from the lug 45 by the hand grip 44 when pulled upon and thus the receiver body 16 will tilt forwardly and its cover 45 or top 18 automatically open.

Connected to the pivots 20 for the links 19 and with the receiver body 16 forwardly thereof at opposite ends of the same to be interiorly of the said receiver body are link chains 52 which serve 55 to limit the forward tilting of the said body 16 and the opening of the cover or top 18 under tilting action of the said receiver body.

The uprights or posts 10 may be of any desired length to elevate the receiver body 16 and 60 the box 27 at the height desired from the ground or a foundation upon which the stand A is arranged.

The door 28 is held closed by a spring catch 55 upon the box 27.

65 The box 27 cannot swing horizontally from its normal position at right angles to the stand A except by releasing the dog or pawl 47 from the keeper extension 48. To tilt the receiver body 16, independently of the turning of the mailbox, 70 it is necessary that the trigger latch 42 be released from the lug 45 yet this body 16 will not tilt forwardly until the grip 44 is pulled upon after the release of the trigger 42 is just mentioned.

75 Assuming that the receiver body 16 is in nor-

mal closed perpendicular position and that the mailbox 27 is at right angles to the stand A for projecting forwardly thereof and that the receiver body and box contain mail matter for collection, to gain access to the receiver body the trigger 42 is manually operated, a pull is exerted upon the hand grip 44 and the said body 16 will be released from its latched perpendicular position and tilted forwardly of the stand A. This forward tilting of the body 16 causes the lid or cover 18 to automatically open giving full access to said body for the removal of mail matter therefrom or for the placing of mail matter therein. On return movement of this body 16 to perpendicular position it becomes automatically closed and latched by the trigger 42 engaging the lug 45 in a manner as before stated. For convenience in the placing of mail matter within the box 27 by a user or owner and also for the placing of mail matter within the body 16 it is required that the cranked control lever 49 be manually operated causing the release of the pawl or dog 47 from the keeper extension 48 so that the bracket for the said mail box 27 may be freely swung laterally beyond one end of the stand A to be in position readily accessible to said user or owner. Simultaneously the latching trigger 42 through the engagement of the lug 45 on the arm 46 causes the receiver body to be automatically tilted forwardly and become open 30 for the placing of mail matter therein. The control lever 49 is operated only for the release of the pawl or dog 47 from the keeper extension 48 whereby the said bracket for the mail box 27 can be swung horizontally beyond one end of the stand away from the receiver body 16. As long as the lug 45 is engaged with the latching trigger 42 the arm 46 will have leverage action on the said trigger 42 for the moving of the body 16 forwardly to an open position or reversely to a 40 closed position.

What is claimed is:

1. An apparatus of the kind described comprising a stand, receiving and delivering bodies carried by said stand, one of said bodies being 45 swingable vertically and the other of said bodies swingable horizontally, a lid for the vertically swingable body and connected to the latter for opening and closing movements, means connecting the lid with the stand for effecting the automatic opening of the said lid on movement of the vertical swingable body in one direction and also the automatic closing of the said lid when the said body swings in the reverse direction, and manually operable means for latching both of 55 said bodies against swinging movement and automatically releasing one of said bodies for movement independently of the other body.

2. An apparatus of the kind described comprising a vertically swingable body, a horizontally swingable body, a lid mounted on the vertical swingable body for opening and closing the same, means active upon the lid on movement of the vertically swingable body for automatically opening and closing said lid, means manually controlled for normally locking both bodies against swinging movements, and means associated with the last-named means for releasing the horizontally swingable body therefrom and allowing movement of said bodies independently 70 of each other.

3. An apparatus of the kind described comprising a vertically swingable body, a horizontally swingable body, a lid mounted on the vertical swingable body for opening and closing the 75

same, means active upon the lid on movement of the vertically swingable body for automatically opening and closing said lid, means manually controlled for normally locking both bodies against swinging movements, means associated with the last-named means for releasing the horizontally swingable body therefrom and al-

lowing movement of said bodies independently of each other, and means for limiting the movement of the vertically swingable body on the opening of its lid, the said bodies being arranged adjacent to each other and normally projected at right angles to one another.

5 NICK C. HELTEN.
